United States Patent Office

Des. 225,787
Patented Jan. 2, 1973

225,787

KITCHEN BLENDER BASE

Monte L. Levin, New York, N.Y., assignor to Scovill
Manufacturing Company, Waterbury, Conn.

Filed Apr. 30, 1971, Ser. No. 139,313

Term of patent 14 years

Int. Cl. D7—04

U.S. Cl. D89—1

Fig. 1

Fig. 2

Fig. 3

*Fig. 4**Fig. 5**Fig. 6*

FIG. 1 is a perspective view of a kitchen blender base showing my new design;

FIG. 2 is a top plan view;

FIG. 3 is a side elevational view;

FIG. 4 is a front elevational view;

FIG. 5 is a rear elevational view; and

FIG. 6 is a bottom plan view.

I claim:

The ornamental design for a kitchen blender base, as shown.
